UNITED STATES PATENT OFFICE.

RUDOLF E. HELLMUND, OF SWISSVALE, PENNSYLVANIA, ASSIGNOR TO WESTINGHOUSE ELECTRIC AND MANUFACTURING COMPANY, A CORPORATION OF PENNSYLVANIA.

SYSTEM OF CONTROL.

1,295,894.

Specification of Letters Patent.

Patented Mar. 4, 1919.

Application filed March 1, 1917. Serial No. 151,647.

To all whom it may concern:

Be it known that I, RUDOLF E. HELLMUND, a citizen of the United States, and a resident of Swissvale, in the county of Allegheny and 5 State of Pennsylvania, have invented a new and useful Improvement in Systems of Control, of which the following is a specification.

My invention relates to systems of control and especially to that type of system 10 wherein auxiliary-machine armatures are employed in conjunction with the main machines to effect both accelerating and regenerative operation thereof.

The object of my invention is to provide a 15 system of the above-indicated character which shall be relatively simple and inexpensive in construction and effective and reliable in operation to accomplish accelerating or regenerative operation of the main machine or machines without the use of resistors.

More specifically stated, it is the object of my invention to provide, in conjunction with one or more main machines, a plurality of 25 auxiliary mechanically-connected armatures, one of which is connected in series relation with, and the other of which is connected in parallel relation to, the main machine or machines, each of the auxiliary armatures being provided with a subdivided field winding the parts of which are respectively energized by the main-circuit current and by current from the corresponding auxiliary armature.

My invention may best be understood by 35 reference to the accompanying drawing, wherein Figure 1 is a diagrammatic view of the essential parts of a system of control embodying my invention; Fig. 2 is a sequence 40 chart of well-known form for indicating the preferred order of operation of the switches illustrated in Fig. 1 during both accelerating and regenerative operation; Fig. 3 and Fig. 4 are simplified diagrammatic views illustrating the circuit connections under motoring or accelerating conditions and under 45 regenerative conditions, respectively; and Fig. 5 is a diagrammatic view of a modification of a portion of the circuits shown in 50 Fig. 1.

Referring to the drawing, the system shown comprises suitable supply-circuit conductors respectively marked "Trolley" and "Ground;" a main dynamo-electric machine 55 having an armature A and a field winding F

of the series type; a conventionally-illustrated reversing switch RS, of any familiar form, for reversing the electrical relations of the main armature and field winding; a plurality of suitable switching devices LS 60 and 1 to 15, inclusive; and an auxiliary motor-generator or "booster set," comprising a motor or driving armature 20 that is mechanically connected to a driven or generator armature 21 by a shaft 22, or otherwise. 65

The auxiliary motor armature 20 is provided with a subdivided field winding 23 of the series type, while the auxiliary generator armature 21 is provided with a similar type of subdivided field winding 24. To impose 70 a certain mechanical load upon the series-excited motor-generator set and thus preclude any possibility of unduly high speed thereof, irrespective of the electrical load conditions, a suitable blower 25, for example, 75 for furnishing ventilating air to the main machine or machines, may be utilized.

The switches 1, 2 and 3 are associated with different tap-points of the auxiliary motor-field winding 23 to connect it to the main 80 machine, and switches 4, 5 and 6 perform a similar function with respect to the auxiliary-generator field winding 24. Switches 7, 8, 9 and 10 collectively act in the capacity of a reversing switch, switches 7 and 9 being 85 employed for effecting the traversal of current through the auxiliary-generator field winding 24 in the one direction during accelerating operation of the main machine, while switches 8 and 10, when closed, serve 90 to produce a reversal of such current, during the regenerative period. Switches 13, 14 and 15 are associated with various selected points of the main field winding F for varying 95 the active-circuit value thereof.

Inasmuch as the particular system of auxiliary control that is employed in connection with the main circuits just described is immaterial to my present invention, it is not deemed necessary to illustrate or set forth 100 any such system. The operation of the circuits shown will be explained in connection with the sequence chart of Fig. 2 and such description, taken in conjunction with the simplified motoring and regenerating diagrams of Fig. 3 and Fig. 4, is considered as 105 sufficient to fully set forth my present invention.

Assuming that it is desired to effect motoring or accelerating operation of the main 110

machine, the master controller, or its equivalent (not shown) is moved to its first operative position to effect the closure of switches LS, 7 and 9, as indicated by line *a*, Fig. 2, to thereby establish a circuit from the trolley through the switch LS, auxiliary motor armature 20, the entire corresponding field winding 23, conductor 30, the auxiliary generator armature 21, switch 7, conductor 31, the entire auxiliary field winding 24, conductors 32 and 33, switch 9 and conductor 34 to the negative conductor "Ground."

The motor-generator or "booster set" is thus started into operation to produce a relatively low voltage for application to the terminals of the main machine.

Upon the closure of the switches 3, 5, 12 and 15 in position *b* (Fig. 2), to thereby connect the main machine in circuit, the auxiliary generator armature 21 supplies the major portion of the necessary accelerating current, while the supply circuit furnishes the remainder. Consequently, at this time, as shown in a simplified manner in Fig. 3, a new circuit is completed from an intermediate point of the auxiliary motor field winding 23 through switch 3, conductor 37, main armature A, certain contact members (not shown) of the reversing switch RS, the entire main field winding F, switch 15, certain other contact members of the reversing switch RS, conductor 38, switch 12, conductor 39, switch 5 to an intermediate point of the auxiliary generator field winding 24 and thence, through the lower portion thereof, to the negative conductor "Ground," as previously traced.

As indicated by the various arrows in Fig. 3, the inclusion of the main machine in circuit effects a reversal of the initial currents traversing the lower portion of the auxiliary field windings 23 and the upper portion of the field winding 24, while the other parts of the field windings are correspondingly strengthened by the traversal therethrough of additional current in the same direction, the relative magnitude of the various field-winding parts being predetermined by the initially selected switches, in this case, 3 and 5, respectively. It will be understood that, by suitably proportioning the various parts of the illustrated machines, the resultant effect of the connection of the main machine in circuit and the above-described changes in the auxiliary field-winding conditions may be such that the relative voltage distribution between the generator armature 21 and the auxiliary-motor armature 20 will remain substantially the same as before the inclusion of the main machine in circuit or may be varied to impress any desired value of voltage upon the main machine.

The voltage of the auxiliary armature 21 may be subsequently increased by a virtual

upward shifting of the point of interconnection of the main-machine circuit and the auxiliary field winding 24, thus increasing the positive or aiding excitation of the lower portion of the field winding and correspondingly decreasing the negative or opposing excitation of the upper part of the field winding. A corresponding upward movement of the point of connection of the main machine to the auxiliary motor field winding 23 will also serve to effect a gradual increase of the voltage impressed upon the main machine by increasing the lower or negatively-acting portion of the field winding and decreasing the upper or positively-acting part, in this way, gradually reducing the voltage of the auxiliary motor armature 20 and correspondingly increasing the electromotive force impressed upon the main machine.

Such variation of the relative magnitude of the various auxiliary field-winding parts may be readily accomplished by the proper manipulation of the switches 1 to 6, inclusive, as indicated by the sequence chart, Fig. 2. In position *c* of the master controller (not shown), for example, switch 2 may be closed, whereupon switch 3 is opened, while, in position *d*, switch 4 is closed and switch 5 is then opened. In the next position *e*, switch 1 is closed just prior to the opening of switch 2, and thus, the final connections of the main machine and the auxiliary field windings 23 and 24 include the uppermost switches 1 and 4, respectively.

To produce further acceleration of the main machine, switch 14 may be closed and switch 15 then opened, whereby a predetermined portion of the main field winding F is excluded from circuit to effect the desired increase of main-machine speed, in accordance with familiar principles.

Assuming that conditions are suitable for regenerative operation, the main-circuit reversing switch RS is first actuated to its other position to reverse the electrical relations of the main armature and field winding for a well-known purpose, and switches 8 and 10 are also closed to effect a reversal of the interconnections between the auxiliary generating armature 21 and its field winding 24.

Switches LS and 2, 4, 11 and 13 may then be closed, whereby a relatively small negative voltage is initially impressed upon the main machine from the auxiliary generating armature 21, the circuit being established from one terminal of the auxiliary armature through the switch 8, conductor 32, corresponding auxiliary field winding 24 in the reversed direction, conductor 31, switch 10, conductor 38, main reversing switch RS in its reversed position, switch 13, a relatively small portion of the

main field winding F, reversing switch RS, the main armature A, conductor 37, intermediate switch 2, a predetermined lower portion of the auxiliary motor field winding 23 and conductor 30 to the other terminal of the auxiliary-generator armature 21.

Such initial impression of a negative voltage upon the reversed main machine, now 10 acting as a series generator, causes a rapid building up, of the regenerated voltage in the proper direction, as will be understood.

As soon as the main-machine voltage and current have increased to suitable operating values, the currents traversing the upper portion of the auxiliary-generator field winding 24 and the lower portion of the auxiliary-motor field winding 23 are reversed, with respect to the corresponding currents 20 during acceleration, as clearly shown by the arrows in the simplified diagram of Fig. 4, by reason of the connection of the main machine to the selected intermediate points of the auxiliary field windings.

25 Thus, both portions of the auxiliary-generator field winding 24 act cumulatively and induce a relatively strong positive counter-electromotive force in the auxiliary armature 21. At the same time, the current relations in the two portions of the auxiliary-motor field winding 23 are differential or opposed, the one to the other, to produce a temporary decrease of the voltage of the corresponding auxiliary armature 20.

35 Regulation of the regenerative system to compensate for the gradual decrease in main-machine speed preferably comprises the gradual increase of the active circuit value of the main field winding F by the 40 closure of switch 14 and the subsequent opening of switch 13 and again by the closure of switch 15 just prior to the opening of switch 14, as indicated by positions b' and c' of the sequence chart, Fig. 2.

45 In position d', switch 5 is closed and switch 4 then opened to vary the relative magnitude of the parts of the auxiliary-generator field winding 24 that are traversed by the main regenerative current and the 50 auxiliary-armature current, and thereby produce a decreased main-machine voltage.

In position e', switch 3 is closed, whereupon switch 2 is opened, thus decreasing the negative effect of the auxiliary field winding 23 and correspondingly increasing the portion of the total voltage that is absorbed by the series-related auxiliary machine armature 20 and correspondingly decreasing the regenerated voltage of the main armature A. In the final position f', switch 6 is closed and switch 5 is then opened to further continue the desired distribution of voltages between the various machines.

Thus, by suitable proportioning of parts, 65 the regenerated voltage of the main armature

may be gradually reduced to a relatively low value, while the voltage of the auxiliary armature 20 correspondingly increases to absorb the remaining voltage necessary to insure regenerative operation. 70 I have thus provided a relatively simple set of circuits for effecting both accelerating and regenerative operation of a main machine without the use of either main or auxiliary-circuit resistors, whereby a simple, inexpensive and economical control system is obtained.

I desire it to be understood that the expression "connected * * * in parallel relation to said main armature", as used in the 80 claims, reference being had to the auxiliary-generator armature 21, is intended to cover other equivalent circuit arrangements, such as the connection of the generator armature substantially across the supply circuit. 85 Furthermore, I have intended to cover equivalent auxiliary field-winding connections, such as the use of a circuit comprising inductive and non-inductive resistors 26 and 27, respectively, in parallel relation to an auxiliary field winding, and connection of the main-machine circuit to the inductive resistors, the non-inductive resistors being varied to effect the desired regulation, as indicated in Fig. 5. 90 95

I do not wish to be restricted to the specific circuit connections or arrangement of parts herein set forth, as various modifications thereof may be effected without departing from the spirit and scope of my invention. I desire, therefore, that only such limitations shall be imposed as are indicated in the appended claims. 100

I claim as my invention:

1. In a control system, the combination 105 with a main dynamo-electric machine having an armature and a field winding, of a plurality of auxiliary dynamo-electric machine armatures respectively connected in series relation with, and in parallel relation to, said main armature and each provided with a field winding that is energized in accordance with different currents, said field windings being subdivided and the parts of each field winding, under predetermined 110 conditions, being energized by different circuits. 115

2. In a control system, the combination 120 with a main dynamo-electric machine having an armature and a field winding, of a plurality of auxiliary dynamo-electric machine armatures respectively connected in series relation with, and in parallel relation to, said main armature and each provided with a subdivided series-related field winding, the parts of each field winding being respectively energized, under predetermined 125 conditions, by different circuits.

3. In a control system, the combination 130 with a main dynamo-electric machine hav-

ing an armature and a field winding, of a plurality of auxiliary dynamo-electric machine armatures respectively connected in series relation with, and in parallel relation to, said main armature and each provided with a field winding partially energized in accordance with main-circuit conditions and partially energized in accordance with respectively predetermined auxiliary-armature 10 conditions.

4. In a control system, the combination with a main dynamo-electric machine having an armature and a field winding, of a plurality of auxiliary dynamo-electric machine armatures respectively connected in series relation with, and in parallel relation to, said main armature and each provided with a field-winding partially energized by main-circuit current and partially energized by the current traversing the corresponding auxiliary armature. 20

5. In a control system, the combination with a main dynamo-electric machine having an armature and a field winding, of a plurality of auxiliary dynamo-electric machine armatures respectively connected in series relation with, and in parallel relation to, said main armature and each provided with a plural-part field winding, means for initially energizing a predetermined part of each plural-part field winding in a certain direction, and means for including the main machine in circuit to thereby effect a reversal of the energization of said predetermined 30 parts. 35

6. In a control system, the combination with a main dynamo-electric machine having an armature and a field winding, of a plurality of auxiliary dynamo-electric machine armatures respectively connected in series relation with, and in parallel relation to, said main armature and each provided with a plural-part field winding, means for initially energizing a predetermined part of each plural-part field winding from one of said auxiliary armatures in a certain direction, means for including the main machine in circuit to thereby effect a reversal of current through said predetermined parts, and 40 means for varying the relative magnitudes of said parts. 50

7. In a control system, the combination with a main dynamo-electric machine having an armature and a field winding, of a plurality of auxiliary dynamo-electric machine armatures respectively connected in series relation with, and in parallel relation to, said main armature and each provided with a plural-part field winding, means for initially 55 energizing a predetermined part of each plural-part field winding in a certain direction, means for including the main machine in circuit to thereby effect a reversal of the energization of said predetermined parts, and means for varying the relative magni- 60

tudes of said parts and for varying the active value of the main field winding to regulate the main-machine action.

8. In a control system, the combination with a main dynamo-electric machine having an armature and a field winding, of a plurality of auxiliary dynamo-electric machine armatures respectively connected in series relation with, and in parallel relation to, said main armature and each provided with a plural-part field winding, means for initially energizing a predetermined part of each plural-part field winding from one of said auxiliary armatures in a certain direction, means for including the main machine in circuit to thereby effect a reversal of current through said predetermined parts, and means for varying the relative magnitudes of said parts and for decreasing the active value of the main field winding to effect acceleration of the main machine. 70 80

9. In a system of control, the combination with a main dynamo-electric machine having an armature and a field winding, of a plurality of auxiliary dynamo-electric machine armatures respectively connected in series relation with, and in parallel relation to, said main armature and each provided with a plural-part field winding, means for initially energizing a predetermined part of each plural-part field winding from the parallel-related auxiliary armature in a certain direction, means for including the main machine in circuit to thereby effect a reversal of current through said predetermined parts and an increase of current through the remaining field-winding parts, and means for increasing the magnitude of said initially predetermined parts and for decreasing the active value of the main field winding to effect acceleration of the main machine. 90 100

10. In a control system, the combination with a main dynamo-electric machine having an armature and a field winding, of a plurality of auxiliary dynamo-electric machine armatures respectively connected in series relation with, and in parallel relation to, said main armature and each provided with a plural-part field winding, and means for reversing the field winding of the main machine and of the parallel-related auxiliary machine preliminary to regenerative operation, whereby the main-machine voltage is rapidly built up to thereupon send currents through a part of the field winding of the parallel-related auxiliary machine in an aiding direction and through a part of the field winding of the series-related auxiliary machine in an opposing direction. 110 115

11. In a control system, the combination with a main dynamo-electric machine having an armature and a field winding, of a plurality of auxiliary dynamo-electric machine armatures respectively connected in series relation with, and in parallel relation to, said 120 125

130

- main armature and each provided with a plural-part field winding, means for reversing the field windings of the main machine and of the parallel-related auxiliary machine preliminary to regenerative operation, whereby the main-machine voltage is rapidly built up to thereupon send currents through a part of the field winding of the parallel-related auxiliary machine in an aiding direction and through a part of the field winding of the series-related auxiliary machine in an opposing direction, and means for varying the magnitude of said field winding parts.
12. In a control system, the combination with a main dynamo-electric machine having an armature and a field winding, of a plurality of auxiliary dynamo-electric machine armatures respectively connected in series relation with, and in parallel relation to, said main armature and each provided with a plural-part field winding, means for reversing the field windings of the main machine and of the parallel-related auxiliary machine preliminary to regenerative operation, whereby 25 the main-machine voltage is rapidly built up to thereupon send currents through a part of the field winding of the parallel-related auxiliary machine in an aiding direction and through a part of the field winding of the series-related auxiliary machine in an opposing direction, and means for varying the magnitude of said field winding parts and of the main field winding to compensate for a decrease of the main-machine speed. 30
